UNITED STATES PATENT OFFICE.

WALTER P. MURPHY, OF CHICAGO, ILLINOIS, ASSIGNOR TO UNION METAL PRODUCTS COMPANY, OF CHICAGO, ILLINOIS, A CORPORATION OF DELAWARE.

CAR-END CONSTRUCTION.

Application filed February 4, 1925. Serial No. 6,740.

Railroad freight cars designed and placed in service a decade or more ago are failing to meet present day conditions brought about by the longer trains, heavier locomotives and the classification hump yard. This is particularly true of the end constructions which are being knocked out or broken by the shifting of the lading as the end has been weakened by the torsional and weaving movements of the car in service, which service conditions it was not designed to meet. This is especially true of box and other house cars.

The end constructions fail in numerous ways, the most frequent of which is by the end or corner post breaking or becoming detached from their moorings at top or bottom. The end sills decay and fail to perform their function of supporting the draft sills from drooping. The end sheathing decays so that it not only fails to hold the grain within the car but also does not perform its function as a gusset or bracing to resist the lateral weaving of the car body.

It is expensive to replace an end of a car on account of the cost of material and labor, as well as the time the car is out of service and, therefore, not producing revenue. Investigation shows that the ends of an old box car must be replaced or repaired two or three times a year on an average. All steel car ends are in general use and are easily applied to new equipment as the design can be arranged to accommodate them, but it is expensive in time and material to apply such all steel car ends for repairs, because the old wooden ends walls of the car must be removed before the steel end is applied. The old end is scrapped and wasted.

It is preferable to provide means for reinforcing and strengthening the vulnerable parts of the old end wall of the old car without necessarily removing or replacing the old members thereof, even though such frame members are broken.

It has been proposed to reinforce the end walls of old railway cars by applying a corrugated or otherwise reinforced plate on the outside of the lower portion of the end wall and securing it to the corner post by connecting members so as to transmit the thrust of the shifting load to the side wall of the car. A series of cars built at the same time will vary in width an inch or more after they

have been in service a few years due to the shrinkage of the timber, distortion, looseness of the car parts, etc. It is preferable, therefore, not to flange the reinforcing plate along its vertical edges (or at least not on one edge) but to secure it to a separate connecting member so that the corrugated plate can be applied to any width of car by adjusting the relative position between the connecting member and the corrugated plate. Thus a particular corrugated plate can be used on any one of a series of cars.

The invention resides in providing means for adjustment of the relative position between a reinforcing plate for the end wall of a railway car and its attaching member.

Another object of the invention is to provide a reinforced plate which not only aids in resisting the thrusts of the shifting loads, but also reinforces the old frame members of the end wall to enable them to better resist the lateral weaving movements of the superstructure of the car.

In the drawings:

Fig. 1 is an end elevation of a railway box car showing the device applied thereon.

Fig. 2 is a section along line 2—2 of Fig. 1.

Fig. 3 is an enlarged section on line 3—3 of Fig. 1.

Fig. 4 is a side elevation of Fig. 3.

Fig. 5 is a fragmentary detail of the end of the plate shown in Figs. 3 and 4.

Fig. 6 is a fragmentary detail of the connecting member of Figs. 3 and 4.

The old component parts of the car are shown wherein 1 is the end sill; 2 the end plate; 3 the corner post; 4 the end post; 5 the end diagonal braces; 10 the side diagonal braces; 11 the side plate; 12 the side sill and 13 the end lining.

The reinforced and reinforcing plate 14 is preferably positioned on the outside of the car end wall and is secured to the end sill 1, the corner post 3, end post 4 and diagonal braces 5, as shown in Fig. 1, thus retarding the lateral weaving movements of the superstructure of the car. This plate 14 is preferably provided with horizontal corrugations or other stiffening means, terminating within its opposite edges, which receive the shocks imposed upon the end wall and transmit them to the connecting members 16 which are secured to the car. If these con-

necting members are of angular formation, one leg (17) is secured to the car (by bolt 25) and the other leg (18) is secured to the plate 14 and to the car also if desired. As 5 stated, it is desirable to have adjusting means between the plate and the connecting member, therefore, I provide horizontally slotted holes in either the plate or the connecting member and provide round holes in the other member. Slotted holes may be provided in both the plate and connecting member but it is preferable to have slotted holes in the plate and round holes in the connecting member.

13 It is only necessary to have the means of adjustment at one corner of the car as one connecting member and one end of the plate may be rigidly secured together before the device is assembled on the car.

20 In applying the device to the car, one connecting member 16 is rigidly secured to the plate 14 and the connecting member attached to the car. The bolts 20 (or other securing devices) without their nuts are then placed in the slotted holes 19 at the 25 other end of the plate with their heads towards the car and held in place by pressing the plate 14 against the car. The other connecting member 16 is then placed in position 30 and the bolts 20 moved horizontally in the slotted holes 19 until they register with and project through the round holes 21 in the connecting member, then the nuts are applied to the bolts. This arrangement constitutes means to provide adjustment of the 35 relation of the plate to the connecting member and at the same time to secure these two parts together.

40 The same relation exists between bolts 20, slotted holes 19 and round holes 21 as between bolts 22, slotted holes 23 and round holes 24. However, bolt 22 secures the plate and connecting member to the corner post, while the bolt 20 only secures these parts 45 together. Either of these constructions may be used and come within the scope of this invention.

I claim:—

50 1. In combination with the end wall of a railway car, a metallic plate having corrugations formed therein, said plate provided with holes adjacent one edge thereof, an angle with one leg having holes therein and with the other leg secured to the car, one set of said holes being slotted and the 55 other set of said holes being round, and means detachably engaging said holes to

provide adjustment of the relation of said plate to said angle.

2. In combination with the end wall of 60 a railway car, a metallic plate having horizontal corrugations formed therein, said plate provided with holes adjacent one edge thereof, a vertically positioned angle with one leg having holes therein and with the 65 other leg secured to the car, one set of said holes being slotted and the other set of said holes being round, and means detachably engaging said holes to provide adjustment of the relation of said plate to said 70 angle.

3. In combination with the end wall of a railway car, a metallic plate having horizontal corrugations formed therein terminating within the plate, said plate provided with holes adjacent one edge thereof, a vertically positioned angle with one leg having holes therein and with the other leg secured to the car, one set of said holes being slotted and the other set of said holes 75 being round, and means detachably engaging said holes to provide adjustment of the relation of said plate to said angle.

4. In combination with the end wall of 80 a railway car, a metallic plate having corrugations formed therein, said plate provided with slotted holes adjacent one edge thereof, a member provided with round holes 85 secured to the car, and means detachably engaging said slotted holes and round holes 90 to provide adjustment of the relative position between said plate and said member.

5. In combination with the end wall of 95 a railway car, a metallic plate having horizontal corrugations formed therein, said plate provided with slotted holes adjacent one edge thereof, a member provided with round holes secured to the car, and means detachably engaging said slotted holes and round holes 100 to provide adjustment of the relative position between said plate and said member.

6. In combination with the end wall of 105 a railway car, a metallic plate having horizontal corrugations formed therein terminating within the plate, said plate provided with slotted holes adjacent one edge thereof, a member provided with round holes 110 secured to the car, and means detachably engaging said slotted holes and round holes to provide adjustment of the relative position between said plate and said member.

WALTER P. MURPHY.
